RATCHET FEEDING DEVICE

Filed March 19, 1928

INVENTOR
JOHN A. WALLER.

W. J. Strauss,
ATTORNEY.

UNITED STATES PATENT OFFICE

JOHN A. WALLER, OF LOS ANGELES, CALIFORNIA, ASSIGNOR TO THE STANLEY WORKS, OF NEW BRITAIN, CONNECTICUT, A CORPORATION OF CONNECTICUT

RATCHET FEEDING DEVICE

Application filed March 19, 1928. Serial No. 262,632.

This invention relates to feeding devices of the ratchet type, and as herein shown has been especially designed and adapted for use with mortising tools, but it is by no means limited thereto since it may be put to many other uses.

The object of the invention is to provide a desirable and convenient feeding mechanism easy of operation and comparatively simple in design, and at the same time to provide for easily placing the parts of the device in neutral relation with respect to the device upon which it is being fed, in order that the feeder may be retracted when required. A further object is to provide for retaining said parts in such neutral relation until it is desired to release them.

The invention comprises in part the ratchet feeding mechanism disclosed in my co-pending application, Serial No. 133,028, filed September 1, 1926, the common subject matter being claimed herein. Said invention resides primarily in a sliding yoke or frame carrying a feeding pawl which co-operates with and actuates a locking or checking pawl or dog also carried by said frame, both of the pawls working upon a toothed rack provided on a body which carries the ratchet frame and along which said frame slides as it is operated. Preferably the pawls are actuated and the frame is moved through the medium of a handle movably mounted on said frame. In addition, the preferred embodiment comprises a retainer which engages one of the pawls, such as the feeding pawl, when the pawls are moved to neutral position for retracting the mechanism, this retainer being conveniently released without a separate operation, as through movement of the handle, when it is desired to actuate the device again. The invention resides further in such other novel features, constructions and combinations of parts as may be herein disclosed.

In the accompanying drawings wherein certain embodiments of the invention are disclosed by way of illustration;

Fig. 1, is a side elevation of a mortising tool for doors and the like, this tool being

equipped at the left end with the ratchet feeder hereof.

Fig. 2, is an enlarged view of the feeding device with the near wall of the feeder frame removed to expose the operating parts in elevation, the pawls being retained in neutral position.

Fig. 3, is a cross section taken on line 3—3 of Fig. 2.

Fig. 4, is a horizontal sectional detail through the pawls as indicated by line 4—4 of Fig. 2.

Fig. 5, is a view similar to Fig. 2, the pawls being in operative position; and

Fig. 6, is another similar view showing the pawls in an intermediate position as the device is being actuated to feed the same.

A body, in the form of a channel bar 14 in which is secured a toothed bar or rack 15 having teeth 16, is provided to carry the ratchet feeder and also to support the tool which is to be fed, which tool is illustrated in the present instance as being a mortising tool having a chisel 20 and a knife 55 adapted to mortise a door —D— or the like. Since the tool with which the ratchet is used is immaterial and forms no part of the present invention, a further description thereof is not considered necessary and is not here given.

The ratchet device upon which protection is sought in the present case comprises a sliding yoke or frame 80 which is looped around the body 14 to slide thereon and is provided with a bottom wall 81 having at its forward end an upturned flange and an offset ledge to provide an abutment 81' to engage the work for pressing the latter against the tool. The side walls of the frame 80 are provided with openings 82 and are connected by means of bolts or screws 83 and 83', while a feeding pawl or lever 84 mounted within the frame is provided with lateral extensions 84' which terminate in trunnions 85 mounted in the bifurcations 86 of an operating handle, the lower ends of said bifurcations being pivoted upon the frame by means of a pivoting pin 87 extending therethrough. The rear end of the pawl 84 is provided on the upper side of

its tip with a number of teeth 88 adapted to engage with the teeth 16 of the rack 15, whereby the pawl 84 acts as a feeding pawl for the device. The forward end of pawl 84 is in the form of a short arm or finger 89 which is adapted to ride up on an inclined face 91 of a locking or checking pawl 92 pivoted upon the bolt 83' and having a lower arm 94 which approaches the bottom wall 81 and is engaged by a spring 95 normally urging said pawl 92, and its arm 94, upward to cause the upper tip of the upper arm thereof to engage with the rack teeth 16. A spring 96 disposed around pivot pin 87 normally urges pawl 84 upward into rack-engaging position.

When the handle and its bifurcations 86 are swung forward into the position of Fig. 2, the finger or arm 89 of feeding pawl 84 engages the rides up on face 91 of checking pawl 92, thus withdrawing teeth 88 from engagement with the rack and at the same time depressing pawl 92 and withdrawing it also from the rack, whereby the pawls are placed in neutral position and the entire device is freed for sliding movement along the body bar 14. When the parts reach this position, as seen in Fig. 2, the upwardly and rearwardly curved tip 96' of spring 96 engages in a correspondingly formed notch 98 in the under side of the rear end of feeding pawl 84, and retains this neutral relation of the parts by preventing rearward motion of said pawl 84. However, the end 35 or tip 96' is so rounded and the notch 98 is so formed that a little rearward motion of the handle causes said spring tip 96' to be disengaged from the notch, so that the parts may be moved to the operative position of Fig. 6.

Thus, it will be seen that by movement of the handle 86 forward (that is, to the right in the drawings) the parts will be moved to the neutral position shown in Fig. 2, when the handle reaches the limit of its stroke, the spring tip 96' entering the notch 98 to retain this relation if the handle be left in such position. The frame 80 may then be shifted along bar 14 at will. When the handle 86 is moved rearward, the teeth 88 are soon urged upward by the spring 96 (after release of tip 96' as above explained) into engagement with rack 15, whereupon continued movement of the handle rearward causes the frame 80 to be shifted forward along the bar to feed the device, this being accomplished by reason of the engagement of the teeth 88 with the rack and connection of the handle with the frame and with the pawl 84. This feeding movement having been accomplished, the checking or locking pawl 92, which has ridden over the rack teeth 16, now engages with the rack and prevents return of the frame when the handle is again moved forward to carry the

pawl 84 forward, the pawl teeth 88 then riding over the rack teeth. This movement is best indicated in Fig. 6, and, if it is not desired to place the parts in the neutral position of Fig. 2, the handle movement may be terminated when at the position of said Fig. 6, or the entire stroke of the handle may be completed, since the pawl 84 will be immediately released from spring 96 when return movement of handle 86 is started.

I claim:

1. A ratchet feed comprising a body, a frame movable on said body and carrying an abutment jaw, a handle swingingly mounted on the frame, a feeding pawl mounted on the handle and a locking pawl mounted on the frame, said pawls being adapted to engage said body, said feeding pawl having a finger to engage the locking pawl, whereby upon movement of the handle both of said pawls may be released from the body, and retaining means for engaging one of said pawls when withdrawn from the body to retain the pawls in neutral position.

2. A ratchet feed comprising a body, a frame movable on said body and carrying an abutment jaw, a handle swingingly mounted on the frame, a feeding pawl mounted on the handle and a locking pawl mounted on the frame, said pawls being adapted to engage said body, said feeding pawl having a finger to engage the locking pawl, whereby upon movement of the handle both of said pawls may be released from the body, and retaining means for engaging the feeding pawl when in released position to retain the pawls in neutral relation.

3. A ratchet feed comprising a body, a feeding frame movable on said body, a handle swingingly mounted on said frame, a feeding pawl mounted on the handle and a locking pawl mounted on the frame, both of said pawls normally engaging said body for feeding action, the feeding pawl having a finger adapted to engage the locking pawl upon extreme movement of the handle for withdrawing both pawls from engagement with said body, and retaining means for engaging the feeding pawl when in released position to maintain the neutral relation of the pawls with respect to the body.

4. A ratchet feed comprising a body, a feeding frame movable on said body, a handle swingingly mounted on said frame, a feeding pawl mounted on the handle, and a locking pawl mounted on the frame, both of said pawls normally engaging said body for feeding action, the feeding pawl having a finger adapted to engage the locking pawl upon extreme movement of the handle for withdrawing both pawls from engagement with said body, and retaining means for engaging one of the pawls when in released

position to maintain the neutral relation of the pawls, the retaining means being releasable upon handle movement.

5. A ratchet feed comprising a body, a feeding frame movable on said body, a handle swingingly mounted on the frame, a feeding pawl mounted on the handle and a locking pawl mounted on the frame, both of said pawls normally engaging said body,
10 whereby upon movement of the handle within certain limits the feeding pawl feeds the frame upon one stroke and the locking pawl holds the frame upon the opposite stroke, the feeding pawl having a finger to
15 engage the locking pawl upon extreme movement of the handle, whereby continued movement of the handle releases both pawls, and retaining means for engaging the feeding pawl when in released position to main-
20 tain the neutral relation thereof, said retaining means being movable to releasing position upon actuation of the handle.

6. A ratchet feed comprising a substantially straight bar having a rectilinear rack
25 provided with ratchet teeth, a frame slidably mounted on said bar, a handle pivoted in said frame for oscillatory movement, a feeding pawl pivoted on said handle and adapted to directly engage said rack,
30 whereby upon movement of the handle on its operative stroke, the feeding pawl feeds the frame longitudinally of said bar, a locking pawl pivoted on said frame and adapted to interlock with said rack for holding said
35 frame against movement upon said bar when the handle is moved on its inoperative stroke, and a spring for each pawl normally urging the same into direct engagement with the rack of said bar, said feeding
40 pawl having a finger adapted to engage said locking pawl when the handle has been moved to the full extent of its inoperative stroke, whereby both of said pawls are disengaged from said rack so that said frame,
45 handle and pawls may be moved longitudinally of the rack without operating the handle.

In testimony whereof I affix my signature.
JOHN A. WALLER.
